WILLIAM PHELPS, JR., OF SALEM, MASSACHUSETTS.

Letters Patent No. 83,789, dated November 3, 1868.

IMPROVEMENT IN BLIND-FASTENERS.

The Schedule referred to in these Letters Patent and making part of the same.

To all whom it may concern:

Be it known that I, WILLIAM PHELPS, Jr., of Salem, in the county of Essex, and State of Massachusetts, have invented an Improved Blind-Fastener; and I do hereby declare the following to be a full and correct description of the same, reference being had to the accompanying drawings, in which—

Figure 1 is a perspective view of the lower part of a window-frame and blind having my improved fastener attached;

Figure 2 is a view of the fastener in position, the wood-work being partially removed to show the relations of all the parts;

Figure 3 is a top view of the latch-plate;

Figure 4 is a top view of the confining-plate, which holds the latch-plate in position; and

Figure 5 is a bottom view of the same.

The same letter marks the same part wherever it occurs.

The nature of the invention consists in the peculiar construction of the latch-plate, and in the devices for confining and operating the same, the whole forming a new and improved blind-fastener, as hereinafter more fully set forth.

In the accompanying drawings, A marks a window-sill, forming part of the frame of an ordinary window; B, the lower bar of the frame of the blind, to the under side of which the fastener is attached.

C marks the window-frame, and D the blind-hinges.

E is the latch-plate, shown in perspective in fig. 2, and in plan in fig. 3.

In this plate are four notches, b b and c c, of which the two, b b, alternately catch upon a pin driven into the window-sill when the blind is closed, and upon a staple in the outer wall when the blind is opened.

The notches c c receive the points a a of the confining-plate F, which alternately serve as fulcra for the latch-plate E.

A hole, d, receives the free end of spring s, the reaction of which tends to hold the plate E in contact with the plate F, in the position shown in fig. 2.

A stud, e, serves as a handle to operate the latch-plate.

F is the confining-plate or socket, by which the plate

E is held in place. It is shown in top view in fig. 4, and in bottom view in fig. 5, and in perspective, as attached to the blind, in figs. 1 and 2. It is fastened to the bottom of the lower bar of the blind-frame by screws passing through holes i i.

The peculiar feature of this plate consists in the points a a, which enter the notches c c of plate E, and serve alternately as fulcra for that plate.

A semicircular recess, in one end of the slot in plate F, receives a corresponding projection of plate E, and the two are held in contact by the spring s.

The form and position of this spring, and the recess in which it lies, are clearly shown in fig. 2. Its free end enters a hole, d, in plate E.

The operation is as follows:

When the blind is closed, the inner hook of the latch-plate catches upon the pin f, in the window-sill, in the usual way. It is released by drawing back the end of the plate by means of the stud e, when the point a, farthest from e, becomes the fulcrum upon which the latch-plate turns. The other point, a, becomes the fulcrum when the outer hook of plate E engages with the staple in the wall, arranged to receive it. The spring s gives the required impulse to the latch-plate, by whichever end it may be operated.

The advantage of this invention lies in its simplicity. The fastener consists of but three simple parts, inexpensive, easily made, readily applied, and little liable to get out of order.

Having thus fully described my invention,

What I claim, and desire to secure by Letters Patent, is—

The combination and arrangement of the plates E and F with the spring s, all constructed and applied substantially in the manner and for the purpose specified.

The above specification of my said invention signed and witnessed, at Salem, this 3d day of June, A. D. 1868.

WM. PHELPS, JR.
